UNITED STATES PATENT OFFICE.

KARL WESSEL, OF ST. PAUL, MINNESOTA.

GRASS-CRIMPING MACHINE.

951,863.

Specification of Letters Patent. Patented Mar. 15, 1910.

Application filed May 15, 1908. Serial No. 433,025.

To all whom it may concern:

Be it known that I, KARL WESSEL, a citizen of the United States, residing at St. Paul, in the county of Ramsey and State of Minnesota, have invented certain new and useful Improvements in Grass-Crimping Machines; and I do hereby declare the following to be a full, clear, and exact description of the invention, such as will enable others skilled in the art to which it appertains to make and use the same.

My invention has for its object to provide a simplified and improved grass crimping or curling machine, especially adapted for use to treat marsh grass in the preparation thereof for use as a filler for mattresses, cushions, etc.; and to this end it consists of the novel devices and combinations of devices herein-after described and defined in the claims.

The invention is illustrated in the accompanying drawings, wherein like characters indicate like parts throughout the several views.

Referring to the drawings, Figure 1 is a plan view with some parts broken away and some parts removed, showing the improved machine. Fig. 2 is a side elevation of the said machine; and Fig. 3 is a vertical section taken on the line $x^3 x^3$ of Fig. 1.

The frame-work of the machine is made up of a pair of heavy laterally-spaced pedestal castings 1, spaced apart and tied together by a heavy rod 2 and by a feed table 3, which table has a depression 4 near its delivery end and is provided with an up-turned edge 5 at its extreme delivery end. The other portion of the table 3 is provided with side-boards 6 suitably secured thereto and to the pedestal castings 1, and, as shown, having a transverse tie bar 7 at their inner extremities, which tie bar is located considerably above the said table so as to permit the free feed of the grass under the same. Located adjacent to the up-turned delivery end 5 of the said feed table is a pair of large, heavy and deeply corrugated inter-meshing crimping rollers 8 and 9 that extend transversely of the machine. These rollers are preferably made hollow so that steam may be introduced thereinto to keep them hot and thereby increase their crimping efficiency. Both are provided with heavy hollow trunnions 8^a and 9^a, respectively, which make possible the introduction of steam into said rollers while they are kept under rotation. The trunnions 8^a of the crimping roller 8 are mounted in

fixed bearings on the pedestal castings 1 and one of the trunnions thereof is provided with a relatively large spur gear 10 and relatively small spur gear 11. The trunnions 9^a of the upper roller 9 are journaled in bearing boxes 12 that are mounted to slide vertically in the pedestal castings 1 and are arranged to be adjusted by screws 13 that work with threaded engagement through suitable bearings 14 secured to the tops of said pedestal castings. At their upper ends the adjusting screws 13 are provided with hand wheels 15, by means of which they may be moved.

Located just over the depressed portion 4 of the table 3 is a pair of transversely extended rollers 16 mounted in suitable bearings on the pedestal castings 1 and provided with projecting picking teeth or spikes 17 that preferably project approximately tangentially therefrom and are turned backward in respect to the direction of rotation of the said rollers. Also mounted in suitable bearings afforded by the pedestal castings 1 is a smooth or toothless roller 18, the shaft 80 of which is provided, at one end, with a spur gear 19. The gear 19 meshes with similar gears 20 on the shafts of the rollers 16, but the said two gears 20 are spaced apart so that they do not intermesh with each other. The roller 18 is located below the two rollers 16, half-way between the same, and the depressed portion 4 of the feed table is cut away to afford clearance for the said roller 18. This roller 18 is arranged to fill, as nearly as possible, the space above the intermediate portion of the depressed table section 4, through which the teeth of the two rollers 16 do not travel, but the said roller must not, of course, project into the imaginary cylinders described by the points of the teeth 17.

The gear 11 which is carried by the lower crimping roller 8 meshes with a similar gear 21 which is carried by the projecting shaft of the rearmost or right hand roller 16, so that motion will be transmitted from said roller 8 first to the said rear roller 16, thence to the roller 18, and from thence to the other roller 16. The large gear 10 which is carried by the lower roller 8 meshes with a spur pinion 22 that is secured to the hub of the spur gear 23, suitably journaled on one end of the tie rod 2. The gear 23 is engaged by a spur pinion 24 carried by a counter-shaft 25 mounted in suitable bearings on the pedestal castings 1 and provided

with a pulley 26, over which a power-driven belt (not shown) will run to transmit power to the machine.

The grass to be crimped is fed, preferably by hand, and as nearly endwise as possible, into engagement with the first toothed roller 16; and, by this first toothed roller, it will be fed onward to the second, and by the latter it will be fed between the corrugated rollers 8 and 9 and will be crimped or curled in passing between the said corrugated rollers. The toothed rollers have a combing action on the grass, which tends to straighten it out and feed it endwise between the crimping rollers. The driven roller 18 assists in feeding the grass to the rollers and holds the grass up so that it will be engaged by the teeth of the rollers 16. This roller 18 is, therefore, important.

It is, of course, evident that any desired pressure can be put upon the grass in passing between the corrugated rollers 8 and 9 simply by adjusting the upper roller by means of the screws 13.

The machine, while extremely simple, is efficient for the purposes had in view.

What I claim is:

1. In a machine of the kind described, the combination with a pair of crimping rollers, of a feed table for directing the grass thereto, a pair of toothed rollers working from said table immediately in front of said

crimping rollers, and a roller projecting through said table below and midway between the said toothed rollers with its upper surfaces materially above the lowermost lines of travel of the teeth of said toothed rollers, and serving to keep the grass blades raised into engagement with the teeth of said rollers, substantially as described.

2. In a machine of the kind described, the combination with a pair of interlacing corrugated crimping rollers, of a feed table for directing the grass blades to said crimping rollers, provided with a depression immediately in front of said crimping rollers, a pair of toothed rollers working immediately over the compressed portion of said table, a loose roller projecting through the depressed portion of said table, midway between said toothed rollers with its upper surfaces above the lowermost lines of travel of the teeth of said toothed rollers, the teeth of said rollers being inclined backward in respect to their direction of rotation and arranged to move on intersecting arcs, and means for driving said toothed rollers in the same direction, substantially as described.

In testimony whereof I affix my signature in presence of two witnesses.

KARL WESSEL.

Witnesses:

HARRY D. KILGORE,
MALIE HOEL.
